US00D522031S

(12) **United States Design Patent** (10) **Patent No.:** **US D522,031 S**
Siu (45) **Date of Patent:** **** May 30, 2006**

(54) **MONOCULAR**

(75) Inventor: **Cavan Siu**, Bedford, NH (US)

(73) Assignee: **Insight Technology, Inc.**, Londonderry, NH (US)

(**) Term: **14 Years**

(21) Appl. No.: **29/227,315**

(22) Filed: **Apr. 8, 2005**

(51) LOC (8) Cl. **16-06**

(52) U.S. Cl. **D16/132**

(58) Field of Classification Search ..... D16/130–136, D16/202; 359/409, 411, 631, 809, 815; 250/330, 250/214 VT

See application file for complete search history.

Primary Examiner—Paula A. Greene

(57) **CLAIM**

The original design for a monocular, as shown and described.

DESCRIPTION

FIG. 1 is a perspective view of a first monocular of the present invention;

FIG. 2 is a front view of the monocular of FIG. 1;

FIG. 3 is a rear view of the monocular of FIG. 1;

FIG. 4 is a right side view of the monocular of FIG. 1;

FIG. 5 is a left side view of the monocular of FIG. 1;

FIG. 6 is a top view of the monocular of FIG. 1;

FIG. 7 is a bottom view of the monocular of FIG. 1;

FIG. 8 is a perspective view of a second monocular of the present invention;

FIG. 9 is a front view of the monocular of FIG. 8;

FIG. 10 is a rear view of the monocular of FIG. 8;

FIG. 11 is a right side view of the monocular of FIG. 8;

FIG. 12 is a left side view of the monocular of FIG. 8;

FIG. 13 is a top view of the monocular of FIG. 8; and,

FIG. 14 is a bottom view of the monocular of FIG. 8.
